Application September 22, 1937, Serial No. 165,010

5 Claims. (Cl. 15—166)

This invention relates to brushes adapted particularly for the formation or painting of letters or characters as for example in the drawing or painting of price or display cards in stores or 5 other establishments.

The procedure has been generally to use soft bristle or hair brushes of different sizes, but with these ordinary brushes it is difficult, particularly for unskilled persons, to obtain unwavering lines 10 or stripes of uniform width, as any variation in pressure on the brush will result in corresponding varying widths of the lines or stripes.

An important object of my invention is to provide for these ordinary brushes a nib or guide 15 element to be attached to the brush handle with its outer end overlying the bristles and slotted longitudinally to provide teeth, the outer end of the guide element being substantially in the form of a fine tooth comb structure overlying 20 the bristles to form a backing therefor as they are moved over the surface to which the lettering or characters are to be applied, the width of the comb end corresponding to the size of the brush and determining the width of the line or 25 stripe to be formed, capillary attraction holding the bristles at their ends spread across the full width of the comb end so that the bristles will apply the ink, paint, or marking medium to the surface while the slits between the comb teeth 30 will serve as retainers for the ink or marking medium for feeding to the bristles. The flexibility of the comb structure will permit the brush bristles to form full solid lines over rough surfaces, as well as smooth surfaces, and uniform 35 width and unwavering lines or stripes can then be readily and rapidly acquired by unskilled persons.

The ordinary small soft bristle brushes have small ferrules which do not provide an efficient 40 grip for the brush, and therefore another important object of the invention is to provide a substantial grip for said brushes, the grip being preferably in the form of an elastic sleeve of suitable material, such as rubber, which sleeve will 45 afford an adequate grip for easier manipulation of the brush and may also serve to secure the guiding point or comb element to the brush handle in proper position relative to the brush bristles.

50 A further object of the invention is to increase the ink or marking medium holding capacity of the brush, this being accomplished by providing a recess or space in the body of the guide element and communicating with the spaces or slits between the comb teeth, these spaces and the cav-

ity, as well as the bristles, receiving a charge of marking medium when the brush is dipped therein, the marking capacity of the brush being thus materially increased for each dip into the marking medium.

5 A further object is to provide an arrangement so that the guide element may be readily detached from the brush if it is desired to use the brush in the ordinary way.

Other features and advantages of my improved brush will be referred to in the following specification and description in connection with the accompanying drawing, in which drawing:

Figure 1 is a side elevation of the brush structure;

Figure 2 is a front elevation;

Figure 3 is an enlarged section on plane III—III of Figure 2;

Figure 4 is a front elevation of the guide element;

Figure 5 is a rear view of the guide element;

Figure 6 is a section on line VI—VI of Figure 3 showing a modified arrangement.

The brush proper shown is of the ordinary type comprising a handle 10, usually of wood, a tapering ferrule 11, usually of metal, and the bristles 12 secured in the end of the ferrule. In accordance with my invention I provide a guide element designated as a whole A. This element is of elongated or oblong shape and comprises the body part 13 for application to the brush holder or ferrule, and the comb end formed by the longitudinal slits 14 between the comparatively slender teeth 15, this comb end and part 35 of the body 13 overlying the bristles 12.

The bottom side of the guide element where it overlays the bristles is preferably flat, and the under side of the inner end of the body may be of a shape to properly seat against the ferrule 40 11. As shown at 16, the ferrule may be flat on one side to form a seat for the flat under side of the body 13 in engagement therewith. To hold the guide element in proper position a sleeve 17 may be provided for intimately surrounding the 45 ferrule and for clamping the guide element to the ferrule. Preferably the sleeve 17 is of elastic material such as rubber and of an outer diameter so as to provide a substantial grip for the brush which will enable the brush structure to be more 50 readily manipulated. This grip sleeve could be of plastic or molded material and provided with a recess 18 opposite the flattened or indented part 16 of the ferrule in order to form a pocket into which the guide element could be accurately in- 55

serted, as shown in Figure 6. The inner end of the guide element body is preferably tapered so as to facilitate its insertion between the grip sleeve and the ferrule.

5 The guide element could be of metal, but is preferably of softer material such as hard rubber, Celluloid, or plastic. The setting of the guide element is such that its end or guiding edge E will be in line with the ends of the bristles or just 10 a slight distance behind the bristle ends. When the brush is dipped into ink or other marking material, the bristles and the slits 14 of the guide element will be charged with marking material, capillary attraction causing the bristles to spread 15 at their ends for full width engagement with the end of the comb so that when the brush is now drawn along the surface to be marked, the edge E of the guide element will engage the surface to support the brush and take up the pressure 20 while the bristles will apply the marking medium to the surface, the width of the line or stripe being determined by the width of the comb end of the guide element so that the lines or stripes will be of uniform width throughout if the edge E of 25 the guide element is kept at right angles to the direction of the line or stripe. If narrower lines are desired, the brush is turned to angle the edge E relative to the direction of marking, and as the comb end is flexible laterally, waving lines 30 can be readily made, all under accurate guidance of the guide element. The brush structure may be thus easily manipulated by unskilled persons for accurate and uniform lettering or other markings.

35 The comb end of the guide element, acting as a reservoir for marking medium to be fed to the bristles, materially increases the marking capacity of the brush structure for each dip into the marking medium. In order to further increase 40 the marking capacity per dip, the guide element may be provided with a cavity or recess 19 in its under side with the recess located to communicate with the inner ends of the slits 14 so that when the brush is dipped in the marking medium, the 45 cavity will be filled and the contents gradually fed to the comb slits and to the bristles as the brush is manipulated.

The comparatively slender teeth 15 will permit enough spring action to follow the brush over 50 rough surfaces so that the brush may apply marking material to fully cover the rough surface for unbroken lines of uniform width.

The brush structure can be easily used for ruling lines, as the guide element will form a guide 55 abutment for engagement with a ruler edge, and the ruler may be laid flat on the surface to be marked instead of being held up above the surface as would be necessary if the ordinary brush were used. The brush with the guide element 60 thereon could also be attached to a compass structure to make true and even lines, which would be almost an impossibility with the ordinary brush.

The guide element also serves to take the 65 weight off of the bristles and prevent distortion thereof when the brush is stood in water to keep the bristles soft after a period of use of the brush. If it is desired to use the brush in the ordinary manner, the guide element may be readily withdrawn, and as readily re-applied when its use is desired.

I have shown and described a practical and efficient embodiment of the features of my invention, but I do not desire to be limited to the exact 70 construction and arrangement shown and de-

scribed, as changes and modifications may be made without departing from the scope of the invention.

I claim:

1. A guide element for cooperation with a soft bristle lettering brush and comprising a body part adapted for mounting on the brush handle and an outer part for overlying the brush bristles, said outer part terminating in a straight contact edge and being slotted longitudinally inwardly from said edge to leave a row of teeth, said slits serving as reservoirs for marking fluid to be fed to the bristles and said edge being adapted to engage with the surface to be marked to guide the movement of the bristle ends over said surface and to determine the width of the line marked by the bristle. 5

2. A guide element for cooperation with a soft bristle lettering brush and comprising a body part adapted for mounting on the brush handle and an outer part for overlying the brush bristles, said outer part terminating in a straight contact edge and being slotted longitudinally inwardly from said edge to leave a row of teeth, said slits serving as reservoirs for marking fluid to be fed to the bristles and said edge being adapted to engage with the surface to be marked to guide the movement of the bristle ends over said surface and to determine the width of the line marked by the bristles, said guide element body having a recess therein communicating with the inner ends of said slits and arranged to receive marking fluid when the brush is dipped and to feed the fluid through the slits for delivery to the brush bristles. 20

3. The combination with a lettering brush comprising a holder and soft bristles extending from one end thereof, of a guide element comprising a body part and an outer part slotted longitudinally to provide a row of comb teeth, a sleeve on the end of said holder serving as a grip and as a means for engaging the guide element body to secure it to the holder with its comb end overlying and in contact with the bristles and with the teeth ends substantially paralleling the bristle ends whereby when said brush is used the teeth ends will engage the surface to be marked and will define the width of the marking by the bristles, said teeth being flexible laterally but comparatively inflexible vertically. 30

4. A guide attachment for a soft bristle lettering brush in the form of a comb structure adapted to be mounted by its body on the brush holder with its comb teeth overlying and in contact with the brush bristles for engagement of the teeth end with the surface to be marked and to determine the width of the line marked by the bristles, said teeth being flexible laterally but comparatively stiff vertically. 40

5. The combination with a lettering brush comprising a holder and soft bristles extending from one end thereof, of a guide element comprising a body part and an outer part slotted longitudinally to provide a row of comparatively fine comb teeth, an elastic sleeve on the end of said holder serving as a grip and as a means for receiving the body part of said guide element to secure said element to the holder with its comb teeth overlying and in contact with the bristles and with the tooth ends substantially paralleling the bristle ends whereby when said brush is used the teeth ends will engage the surface to be marked and will define the width of the marking by the bristles. 50
